VALVE STEM

John C. Crowley, Cleveland Heights, Ohio, assignor to The Dill Manufacturing Company, Cleveland, Ohio, a corporation of Ohio

Original application March 26, 1934, Serial No. 717,327, now Patent No. 2,094,264, dated September 28, 1937. Divided and this application March 10, 1937, Serial No. 130,051

1 Claim. (Cl. 251—144)

This invention relates to a valve stem and valve for inflatable articles such for example as pneumatic tires.

This application is a division of application Serial No. 717,327, filed March 26, 1934, and now Patent No. 2,094,264, granted September 28, 1937.

An object of the invention is to provide a combined valve stem and valve that is so constructed as to eliminate the use of separate valve insides 10 and valve springs in the stem.

Another object is to provide a combined valve stem and valve such as above specified, which is constructed in its major part of molded rubber.

A further object is to provide a combined valve stem and valve structure which comprises a minimum number of parts that will not readily wear out or become inoperative and, in fact, will last for the life of the tire tube to which it is attached.

Further and additional objects and advantages will become apparent hereinafter during the following description of an embodiment of the invention which is illustrated in the accompanying drawing wherein

Fig. 1 is a sectional view on a somewhat enlarged scale of a valve stem and valve embodying the invention.

Fig. 2 is a view similar to Fig. 1 showing the stem as it is molded and before the valve pin and valve have been added thereto, and

Figs. 3, 4 and 5 are sectional views taken respectively on lines 3—3, 4—4 and 5—5 of Fig. 1 looking in the direction of the arrows.

Referring to the drawing, the valve stem comprises a base 10 and a stem proper 11, said base 35 and stem proper being integral and formed of molded rubber. There is a bore 12 extending from the inner side of the base 10 outwardly of the stem to the point 13 which is the inner end of an internal portion 14 of the valve stem, such 40 portion 14 being integrally connected to the stem between the points 13 and 15. Outwardly of the point 15 the internal portion 14 extends into an enlarged bore 16, there being an annular space 16a between the portion 14 and the wall of the bore 16. The bore 16 is connected to the bore 12 by means of arcuate slots 17 located on diametrically opposite sides of the portion 14 and extending downwardly thereof from the point 15 to below the point 13. The outer end of the 45 portion 14, that is the end that is in the enlarged bore 16, is provided with a transverse groove 18 for a purpose later to be explained.

The stem 11 at its outer end is provided with a bore 19 communicating with a passage 20 50 formed in a metal insert 21 which has its inner

end provided with annular laterally projecting ribs 22 and which is arranged in a counterbore formed in the outer end of the stem. The insert 21 has a threaded end projecting beyond the end of the stem and is molded into the end of the stem as clearly indicated in the drawing, to become, in effect, an integral part of the stem. The bores 16 and 19 in the stem are connected by a restricted passage that is formed by an inwardly extending annular tapered projection 23 integral with the stem and providing a tapered or conical seat on its underside against which a conical valve 24 can seat. The conical valve 24 carries the inwardly or downwardly extending portion 25 having at its inner end a projection 26 or transverse rib 26 interfitting the slot 18 in the outer end of the portion 14 of the stem. The valve 24 also carries an outwardly extending valve pin 27, the outer end of which lies substantially flush with the outer end of the insert 21. In mounting the valve in the stem the valve 24 and its extension 25 are forced through the opening defined by the internal projection 23 of the stem, it being understood that since the stem is formed of rubber said opening may be sufficiently distorted, under force, to allow the valve to be pushed therethrough, after which the projection will return to its normal configuration defining the restricted opening. The projection or rib 26 on the downwardly extending portion 25 of the valve will engage in the slot 18 of the portion 14 of the stem and the valve and portion 14 will then move together. Although the valve for purposes of assembly may be pushed through the opening defined by the projection 23, it will be understood that when once mounted in the stem the air pressure will not be sufficient to force the valve outwardly through said opening and that the conical valve will bear against the complementary conical seat afforded by the underside of the projection 23 and thus seal the passageways through the stem.

The base 10 of the stem may be vulcanized directly to and molded in position upon a tire tube and the stem and tube, in effect, made an integral structure. When the tire tube equipped with such stem is mounted in a tire casing and placed upon a wheel rim the stem will be pulled through the rim opening and when the tube is inflated will be held in extended position.

In inflating the tube an air chuck or other fitting on an air line is applied to the outer end of the metal insert 21 and the valve pin 27 is depressed by the usual means for this purpose that is arranged in the conventional air chucks,

the depression of the valve pin 27 in turn causing an unseating of the valve 24 and a compression of the portion 14 of the stem, thus providing an uninterrupted air passageway through the stem 5 into the tube, which passageway includes the passage 20 through the insert, the bore 19, the restricted opening defined by the projection 23, the bore 16 the annular space 18a between the portion 14 and the wall of the bore 16, the arcuate slots 17 and the bore 12.

When the tube has been properly inflated removal of the air chuck from the metal insert 21 allows the portion 14 which has been compressed to expand to its normal position and to thus bring the valve 24 into sealing engagement with the valve seat formed on the projection 23. Of course, an air gauge or other device can be applied to the outer end of the insert and the valve 24 moved off its seat in a similar manner.

20 It will be noted that the passageways for the air through the stem are of ample magnitude to allow quick inflation and deflation of the tube and that the stem and valve seat being one integral molded structure is sturdy and will last 25 for the life of the tube.

A combined valve stem and valve such as has just been described possesses the advantage of being inexpensive, inasmuch as it eliminates the necessity of the use of separate valve insides 30 and valve springs in the stem. In addition, the stem also possesses the useful function of a rubber stem which allows the stem to pull through

the rim opening in the case of quick deflation of the tube such as occurs with a puncture or blow-out.

Although a single embodiment of the invention has been illustrated and described herein, it should be understood that the invention is susceptible of various modifications and adaptations within the scope of the appended claim.

Having thus described my invention I claim:

A combined valve and valve stem comprising a 10 molded rubber stem adapted to be connected to a tire tube, said stem being provided with a bore extending inwardly from the outer end of the stem toward its inner end and with a bore extending from the inner end of the stem toward its outer end, a rubber portion integrally molded in said stem between said bores and extending into said first named bore and of less diameter than said first named bore and provided at its free end with a transverse slot, arcuate slots 20 formed in said stem adjacent said portion and connecting said bores, means integral with the stem intermediate the ends of said first named bore forming a restricted opening and a valve seat, and a conical valve having a pin extending through said opening toward the outer end of the stem and an inwardly extending projection engaging the transverse slot in the end of said portion whereby said valve is normally held seated by said portion against said valve seat to seal the 25 opening.

JOHN C. CROWLEY.
